MACHINE FOR USE IN LASTING SHOES

Charles A. Robinson, Salem, Mass., assignor to
United Shoe Machinery Corporation, Flemington, N. J., a corporation of New Jersey

Application November 17, 1943, Serial No. 510,654

14 Claims.

(Cl. 12—14)

This invention relates to machines for use in lasting shoes. A special object in view is to provide improvements in machines for lasting the toe ends of welt shoes, and the invention is accordingly herein illustrated as applied to such a machine, but it will be understood that it is not thus limited in its applicability.

In lasting the toes of welt shoes it is the common practice to apply a binder wire about the toe end of each shoe to hold the marginal portion of the upper in upstanding position against the usual lip or shoulder on the insole and to fasten the wire by twisting its ends about tacks driven into the opposite sides of the forepart of the shoe bottom. Later the wire is removed from the shoe and discarded. In a divisional application Serial No. 545,797, filed on July 20, 1944 there is disclosed and claimed a novel upper-holding device or binder adapted to be quickly and conveniently applied and fastened to a shoe and to be used repeatedly in lasting different shoes, its construction being further such that when in place on a shoe it is especially effective in holding the upper securely in lasted position. That binder, as herein shown, has a portion for engaging and holding the upper around the end of the shoe, and has at opposite ends of that portion thereof coil springs arranged to be tensioned lengthwise of the shoe and formed for attachment to the shoe in the angle between the feather and the lip or shoulder of the insole. The tensioned springs thus apply forces in directions parallel to the side edges of the shoe bottom to the portion of the binder extending around the end of the shoe to hold it at all times tightly against the upper and in proper relation thereto. That portion of the binder and the springs may, as herein illustrated, be conveniently made of a single piece of wire. Associated with the springs in the construction shown, as permanent parts of the binder, are members for use in applying the binder and in tensioning the springs and also in fastening the binder to the shoe, these members extending through loops formed on the springs and having prongs arranged to be forced into the marginal portion of the upper and the lip of the insole when the insole has such a lip.

The present invention provides novel means for applying a binder to a shoe, the construction shown being such as to adapt it especially for use to apply a binder formed as above described. Included in that construction are arms arranged to engage opposite end portions of the binder and movable about an axis extending widthwise of the shoe to pull the binder tight against the upper and to tension the above-mentioned springs, the arms being also mounted to swing about axes extending lengthwise of the shoe to carry the end portions of the binder inwardly toward the upper and to force its prongs into the shoe. This bind-

er-applying means is herein shown as manually operated means attached to a power-operated toe-lasting machine constructed as shown in United States Letters Patent No. 2,160,846, granted on June 6, 1939 on an application of F. C. Eastman's and A. F. Pym's; but it will be understood that it is not limited to use in a machine of that particular character or to manual operation, and that in various aspects also binder-applying means embodying novel features of the invention is not limited to use with binders constructed precisely as herein illustrated.

The above and other features of the invention, including various novel details of construction and combinations of parts, will now be more particularly described with reference to the accompanying drawings and thereafter pointed out in the claims.

In the drawings, Fig. 1 is a view partly in right-hand side elevation and partly in section of a portion of the machine shown in the above-mentioned Letters Patent provided with binder-applying means constructed in accordance with the present invention;

Fig. 2 shows the binder-applying means and parts associated therewith in front elevation;

Fig. 3 is a section on the line III—III of Fig. 2;

Fig. 4 is a perspective view of the binder claimed in the divisional application and adapted to be applied to a shoe by the above-mentioned binder-applying means;

Fig. 5 is a plan view of a portion of the structure shown in Figs. 1 and 2;

Figs. 6 and 7 are views partly in front elevation and partly in section illustrating with reference to one end of the binder how it is fastened to a shoe; and

Fig. 8 is a perspective view of the forepart of a shoe with the binder thereon.

As disclosed in the above-mentioned Letters Patent, the machine to which the novel binder-applying means is herein illustrated as attached is provided with a shoe-positioning member 2 (Fig. 2) against which the toe end of the shoe is clamped vertically by a toe rest 4, the member 2 engaging the toe end of the insole and supporting the inner face of the lip *a* of the insole (Figs. 6 and 7) in operating on a welt shoe having an insole provided with such a lip. In the toe-lasting operation the marginal portion of the toe end of the upper is gripped and pulled by a plurality of grippers 6, two of which are shown in Fig. 2, and in time relation to the operation of the grippers the toe end of the upper is wiped heightwise of the last and inwardly over the feather and against the lip of the insole by a pair of toe-embracing wipers 8. The wipers are mounted respectively on wiper holders 10 which are supported and guided for swinging or closing move-

ments laterally of the shoe on a wiper carrier 12 under a cover plate 14 on the carrier. The wiper carrier is supported for movements to advance and retract the wipers lengthwise of the shoe on a pair of links 16 pivotally connected at their upper ends to the carrier near the front end of the latter, and also on the upper end of a lever 18 fulcrumed at 20 between its upper and lower ends. At its lower end the lever 18 carries a roll 22 engaged by a cam 24 for imparting the movements lengthwise of the shoe to the wiper carrier. The links 16 are connected at their lower ends to arms 26, only one of which is shown, these arms being fast on a rockshaft 28 on which is also secured a cam-operated arm 30 for swinging the wiper carrier 12 upwardly about its connection with the lever 18 to cause the wipers to wipe the upper heightwise of the last and for swinging it downwardly to cause them to increase their pressure on the upper wiped inwardly over the feather of the insole. In time relation to their advancing movements lengthwise of the shoe the wipers are closed inward laterally of the shoe, first to engage the upper in the upwiping operation and thereafter to wipe it inwardly over the insole, by forward movement of a slide 32 on the wiper carrier 12, this slide being connected to the wiper holders 10 by links 34 (Fig. 5). The slide 32 is operated yielding through spring means 36 and a rod 38 by a bell-crank lever 40 mounted on the wiper carrier 12, this bell-crank lever being connected by a link 42 to an arm 44 fast on a rockshaft 46 on which is also secured a cam-operated arm 48.

As disclosed in the above-mentioned Letters Patent, the machine comes automatically to a stop after the wipers have wiped the marginal portion of the upper inwardly over the feather and against the lip of the insole and have been raised slightly to decrease their pressure on the upper heightwise of the shoe. This has enabled the operator heretofore to apply a binder wire preliminarily about the toe between the upper and the wiping faces of the wipers, having fastened one end of the wire to a tack driven at one side of the forepart of the shoe bottom. When the machine is again started the wipers are raised a short distance and are also partially retracted and opened. This has enabled the operator to pull the wire farther inwardly against the upstanding margin of the upper, after which the wipers are again moved downwardly and are advanced and closed to apply their full pressure to the upper and to press the binder firmly against it. The machine then comes to a stop a second time, and during this second pause in the operation of the machine the operator has been accustomed to twist the wire around a tack at the other side of the shoe bottom and to sever the wire thus applied from the source of wire supply.

For use, in place of such binder wire, the divisional application discloses a preformed binder 50 (Fig. 4) which may be quickly applied and fastened to a shoe and used repeatedly on a plurality of shoes. The binder 50, in the form herein shown, has a portion 52 of resilient wire for engaging and holding the upstanding margin of the upper around the toe end of the insole, the wire being coiled at its opposite ends to provide springs 54 arranged to be tensioned lengthwise of the shoe as the binder is applied to the shoe. Formed at that end of each spring which is the more remote from the extreme end of the shoe when the binder is in place on the shoe is a loop 56. Associated with the springs, as permanent parts of the binder, are wire members 58 portions

of which extend through the springs lengthwise of the latter. Each member 58 is formed at one end to provide a loop 60 arranged to extend outward laterally of the shoe and also a prong 62 extending inwardly through the loop 56 on the end of the adjacent spring 54 to serve as a fastening for holding the binder on the shoe. By engagement with the loops 60, therefore, the binder may be applied about the toe end of the shoe, the springs may be tensioned lengthwise of the shoe and the prongs 62 may then be forced into the shoe to fasten the binder in place with the springs in tensioned condition. Preferably, as illustrated in Figs. 7 and 8, the ends of the binder are fastened in the angle between the feather and the lip of the insole at the sides of the forepart of the shoe by forcing the prongs through the upstanding margin of the upper and into the lip. It will be understood, however, that in operating on a shoe provided with a so-called shouldered insole, the prongs would be forced into the shoulder of the insole. When the binder is in place on the shoe the springs 54 serve at all times to hold the portion of the binder which extends about the extreme end of the shoe forcibly against the margin of the upper. To limit the tensioning of the springs 54, the members 58 are provided with bent ends 64 for engaging the springs. Preferably small barbs 65 (Fig. 4) are formed on the sides of the prongs 62 which face toward the toe end of the shoe to assist in retaining the prongs in the shoe.

For applying and fastening the above-described binder to the shoe the machine herein shown is provided with binder-applying mechanism which is supported on the wiper carrier 12 and accordingly moves with the carrier both lengthwise and heightwise of the shoe. Secured underneath to the opposite side portions of the carrier at its front end are two downwardly and forwardly extending brackets 66 which support a horizontal rockshaft 68 arranged to extend laterally of the shoe, the brackets being provided with bearing caps 70 for holding the rockshaft in place. Supported on the rockshaft by pins 72 are two upwardly extending arms 74 each of which includes a member 76 adjustable upwardly or downwardly in a guideway in the lower portion of the arm and held in adjusted position by a screw 78. The members 76 are curved inwardly toward each other at their upper ends and are provided with forwardly extending pins 80 arranged to enter the loops 60 of the binder in locations in front of the wipers 8 and substantially opposite the side edges of the shoe bottom, the members being also provided at their upper ends with curved recesses 82 to receive the springs 54 of the binder. By forward swinging movements of the arms 74, therefore, the binder is applied to the margin of the upper about the end of the toe and the springs 54 are tensioned. For imparting such movements to the arms there is fast on the left-hand end of the rockshaft 68 a forwardly extending hand lever 84. The rockshaft is thus turned by the hand lever against the resistance of a spring 86 which normally maintains it in a position determined by a member 88 which is fast thereon and has a projection 90 arranged to engage a shoulder on the adjacent bearing cap 70.

When the binder is thus applied to the shoe by forward movements of the arms 74 the upper ends of the members 76 are far enough apart to provide clearance between the shoe and the prongs 62 of the binder, as illustrated in Fig. 6. For moving the opposite end portions of the binder in-

wardly toward the shoe and for forcing the prongs into the shoe the arms 74 are swung inwardly toward each other about the pins 72. For thus swinging the arms there is mounted to turn about the rockshaft 68 a member 92 confined on the rockshaft between the right-hand bracket 66 and a collar 94 fast on the shaft. The member 92 has thereon two lugs 96 extending forwardly into slots 98 which are formed in plates 100 secured respectively to the front faces of the lower end portions of the two arms 74. In response to turning movement of the member 92 in one direction, therefore, the lugs 96 act on the plates 100 to swing the arms 74 inwardly toward each other as above described. For thus operating the member 92 there is mounted to turn about the right-hand end portion of the rockshaft 68 a hand lever 102 provided with a pin 104 which extends laterally therefrom into an opening in the member 92. Also carried by the hand lever is a pin 106 extending into an opening in a rectangular head 108 formed on the lower end of a rod 110. This rod extends upwardly through a clamp member 112 fast on the right-hand end of the rockshaft 68 and has thereon a compression spring 114 confined between the clamp member and a nut 116 on the rod. The spring 114, therefore, serves to maintain the arms 74 normally at a distance apart determined by engagement of the head 108 of the rod 110 with the lower face of the clamp member 112, and it is against the resistance of this spring that the member 92 is operated by the hand lever 102 to swing the arms 74 inwardly and thus to force the prongs 62 of the binder into the shoe.

In the operation of the machine herein shown, when equipped with the above-described binder-applying means, the operator places the binder shown in Fig. 4 about the toe end of the shoe under the wipers 12 after the machine has come to a stop as hereinbefore described with the wipers slightly raised to decrease their downward pressure on the upper over the feather of the insole, and mounts the loops 60 of the binder over the pins 89 on the members 76. By depressing the hand lever 84 he then swings the arms 74 forwardly to apply to the binder a pull tending to draw it inwardly between the wiping faces of the wipers and the portion of the upper over the feather of the insole. By maintaining this pull on the binder when the machine is again started he draws the binder farther inwardly against the upstanding margin of the upper as the wipers are further raised and retracted and as they are again advanced and closed and moved downwardly to apply their full pressure to the upper. The hand lever is moved far enough downwardly at this time to tension the springs 54 at the ends of the binder as far as permitted by engagement of the bent ends 64 of the members 58 with the ends of the springs. After the machine has come to a stop the second time the operator, while still maintaining the downward pressure on the hand lever 84, swings the lever 102 also downwardly and thereby imparts inward swinging movements to the arms 74 to carry the end portions of the binder inwardly against the upper in the angle between the feather and the lip of the insole and to force the prongs 62 of the binder through the upstanding margin of the upper and into the lip of the insole, as illustrated in Fig. 7. The operator then raises the hand lever 84 to swing the arms 74 rearwardly and thus to withdraw the pins 89 from the loops 60 of the binder, and releases the lever 102 to permit the arms to be

swung outwardly to their initial positions by the spring 114. The binder having thus been applied and fastened to the shoe the operator starts the machine once more to cause the wipers and other parts to be returned to their starting positions. It will be understood that the binder will remain on the shoe until the upper materials have become permanently set in lasted position, after which it will be removed from the shoe prior to the welting operation for use in lasting another shoe.

Having described the invention, what I claim as new and desire to secure by Letters Patent of the United States is:

- 15 1. In a lasting machine, the combination with means for working an upper about an end of a last into lasted position, of means for applying about the end of the upper a binder portable with the last and shoe to hold the upper in lasted position, said binder-applying means comprising arms constructed and arranged to engage opposite end portions of the binder respectively in locations substantially opposite the side edges of the shoe bottom and mounted to swing about an axis extending widthwise of the shoe to pull the binder tight against the upper.
- 20 2. In a lasting machine, the combination with means for working an upper about an end of a last into lasted position, of means for applying about the end of the upper a binder portable with the last and shoe to hold the upper in lasted position, said binder-applying means comprising arms having projections arranged to enter loops formed at opposite ends of the binder, said arms being mounted to swing each about an axis extending widthwise of the shoe to pull the binder tight against the upper.
- 25 3. In a lasting machine, the combination with means for working an upper about an end of a last into lasted position, of means for applying about the end of the upper an upper-holding binder portable with the last and shoe and provided at its opposite ends with loops arranged to extend laterally of the shoe, said binder-applying means comprising members having projections arranged to extend through said loops in directions lengthwise of the shoe, said members being movable lengthwise of the shoe to apply the binder to the shoe.
- 30 4. In a lasting machine, the combination with means for working an upper about an end of a last into lasted position, of means for applying about the end of the upper a binder portable with the last and shoe to hold the upper in lasted position, said binder-applying means comprising members constructed and arranged to engage opposite end portions of the binder and mounted to swing each about an axis extending widthwise of the shoe to pull the binder tight against the upper, said members being also movable toward each other widthwise of the shoe to carry the end portions of the binder inwardly toward the upper.
- 35 5. In a lasting machine, the combination with means for working an upper about an end of a last into lasted position, of means for applying about the end of the upper a binder portable with the last and shoe to hold the upper in lasted position, said binder-applying means comprising arms constructed and arranged to engage opposite end portions of the binder and mounted to swing each about an axis extending widthwise of the shoe to pull the binder tight against the upper, said arms being mounted to swing also about axes extending lengthwise of the shoe
- 40
- 45

to carry the opposite end portions of the binder inwardly toward the upper.

6. In a lasting machine, the combination with means for working an upper about an end of a last into lasted position, of means for applying about the end of the upper a binder portable with the last and shoe to hold the upper in lasted position, said binder-applying means comprising arms constructed and arranged to engage opposite end portions of the binder, a rockshaft supporting said arms and movable about an axis extending widthwise of the shoe to cause the arms to pull the binder tight against the upper, said arms being mounted to swing also relatively to said rockshaft in directions widthwise of the shoe to carry the opposite end portions of the binder inwardly toward the upper, and means for thus swinging said arms.

7. In a lasting machine, the combination with means for working an upper about an end of a last into lasted position, of means for applying about the end of the upper a binder portable with the last and shoe to hold the upper in lasted position, said binder-applying means comprising arms constructed and arranged to engage opposite end portions of the binder, a rockshaft supporting said arms and movable about an axis extending widthwise of the shoe to cause the arms to pull the binder tight against the upper, said arms being mounted to swing also relatively to said rockshaft in directions widthwise of the shoe to carry the opposite end portions of the binder inwardly toward the upper, and mechanism movable about said rockshaft for thus swinging said arms.

8. In a lasting machine, the combination with means for working an upper about an end of a last into lasted position, of means for applying about the end of the upper a binder portable with the last and shoe to hold the upper in lasted position, said binder-applying means comprising arms constructed and arranged to engage opposite end portions of the binder, a rockshaft supporting said arms and movable about an axis extending widthwise of the shoe to cause the arms to pull the binder tight against the upper, a hand lever fast on said rockshaft for thus operating it, said arms being mounted to swing also relatively to said rockshaft in directions widthwise of the shoe to carry the opposite end portions of the binder inwardly toward the upper, and means including another hand lever movable about said rockshaft for thus swinging said arms.

9. In a lasting machine, the combination with means for working an upper about an end of a last into lasted position, of means for applying about the end of the upper a binder portable with the last and shoe to hold the upper in lasted position, said binder-applying means comprising arms constructed and arranged to engage opposite end portions of the binder, a rockshaft supporting said arms and movable about an axis extending widthwise of the shoe to cause the arms to pull the binder tight against the upper, said arms being mounted to swing also relatively to said rockshaft in directions widthwise of the shoe to carry the opposite end portions of the binder inwardly toward the upper, mechanism movable about said rockshaft for thus swinging said arms, and spring means arranged to position said mechanism normally in predetermined relation to the rockshaft and against the re-

sistance of which the mechanism is thus movable about the rockshaft.

10. In a lasting machine, the combination with means for working an upper about an end of a last into lasted position, of means for applying about the end of the upper an upper-holding binder having at its opposite ends prongs arranged to be forced into the shoe to fasten it to the shoe, said binder-applying means comprising mechanism constructed and arranged to pull the binder tight against the upper lengthwise of the shoe by engagement with its opposite end portions and also to force said prongs into the shoe.

11. In a lasting machine, the combination with means for working an upper about an end of a last into lasted position, of means for applying about the end of the upper an upper-holding binder having at its opposite ends prongs arranged to be forced into the shoe to fasten it to the shoe, said binder-applying means comprising members constructed and arranged to engage the opposite end portions of the binder, means for moving said members lengthwise of the shoe to pull the binder tight against the upper, and additional means for moving said members widthwise of the shoe to force said prongs into the shoe.

12. In a lasting machine, the combination with means for working an upper about an end of a last into lasted position, of means for applying about the end of the upper an upper-holding binder having at its opposite ends prongs arranged to be forced into the shoe to fasten it to the shoe, said binder-applying means comprising arms constructed and arranged to engage the opposite end portions of the binder, said arms being mounted to swing about an axis extending widthwise of the shoe to pull the binder tight against the upper and also to swing about axes extending lengthwise of the shoe to force said prongs into the shoe.

13. In a lasting machine, the combination with means for working an upper about an end of a last into lasted position, of means for applying about the end of the upper an upper-holding binder having at its opposite ends prongs arranged to be forced into the shoe to fasten it to the shoe, said binder-applying means comprising arms constructed and arranged to engage the opposite end portions of the binder, a rockshaft supporting said arms and movable about an axis extending widthwise of the shoe to cause the arms to pull the binder tight against the upper, means for thus operating said rockshaft, and additional means movable about said rockshaft for moving said arms inwardly toward each other to force said prongs into the shoe.

14. In a lasting machine, the combination with means for working an upper about an end of a last into lasted position, of means for applying about the end of the upper an upper-holding binder portable with the last and shoe and provided at its opposite ends with prongs arranged to be forced into the shoe and also with loops arranged to extend outward laterally of the shoe, said binder-applying means comprising members having projections arranged to extend through said loops in directions lengthwise of the shoe, and means for moving said members lengthwise of the shoe to pull the binder tight against the upper and for also moving them laterally of the shoe to force said prongs into the shoe.

CHARLES A. ROBINSON.
